(57) **CLAIM**

The ornamental design for a tire carrier, as shown and described.

DESCRIPTION

FIG. 1 is a perspective view of a tire carrier showing my new design, show in its position of use;

FIG. 2 is a front side elevation view thereof;

FIG. 3 is a rear side elevation view thereof;

FIG. 4 is a right side view thereof;

FIG. 5 is left side view thereof;

FIG. 6 is a top side view thereof; and,

FIG. 7 is a bottom side view thereof.

The even broken lines illustrate environmental matter related to the tire carrier that form no part of the design.

The tire carrier is shown on an enlarged scale in FIGS. 2-7.
